UNITED STATES PATENT OFFICE.

JOHN N. FULLER, OF LANSDALE, PENNSYLVANIA.

INTERNAL-COMBUSTION ENGINE.

Application filed May 22, 1926. Serial No. 110,835.

This invention relates to internal combustion engines and its objects are to provide an engine which will utilize the waste heat of the exhaust gases and of conduction, 5 to generate steam for assisting in driving the engine; an engine in which the steam and ignited fuel gases will work simultaneously on the same piston; in which the cylinders will be practically free of carbon 10 deposit at all times, and which will be simple and compact in construction.

These objects, and other advantageous ends which will be described hereinafter, I attain in the following manner, reference 15 being had to the accompanying drawings in which

Figure 1 is a side elevation of an internal combustion engine embodying my invention,

Figure 2 a sectional view taken on line 20 2-2 of Figure 1,

Figure 3 a sectional view taken on line 3-3 of Figure 2,

Figure 4 a fragmentary sectional view taken on line 4-4 of Figure 1,

25 Figure 5 a like view taken on line 5-5 of Figure 1,

Figure 6 a sectional plan view taken on line 6-6 of Figure 1, and

Figure 7 a diagrammatic view showing 30 the functions of the fuel gases in the various cylinders during a cycle of operation.

Referring to the drawings, 1 indicates the crank case of an internal combustion engine, 2 a cylinder block secured to the crank case and having cylinders 3 and water jackets 4 surrounding the cylinders, 5 pistons in the cylinders, 6 connecting rods connecting the pistons with a crank shaft 7 rotatably mounted in the crank case in the 35 usual manner. The crank shaft is geared to a cam shaft 8 by any suitable gearing of a 2 to 1 ratio so that two revolutions of the crank shaft is necessary to rotate the cam shaft one revolution. The cylinder block is provided with intake ports 9 and 40 intake valves 10 for controlling the passage of gases through the ports into the cylinders. Exhaust ports 11 in the cylinder block communicate with the cylinders and are 45 opened and closed by exhaust valves 12. The intake valves 10 and the exhaust valves 12 may be of the usual tappet type operated by proper cams 13, on cam shaft 8, through plungers 14 against the action of springs 50 15 which normally keep the valves closed. The principles of construction thus far de-

scribed form no part of my invention which will now be described.

In order to obtain a maximum transfer of heat from the products of combustion to generate steam, I provide a steam generator 16 on top of the cylinders and shape the bottom wall 17 of the generator to provide a combustion chamber 18 for each cylinder which communicates with the intake and exhaust valves 10 and 12. Each exhaust port 11 is curved upwardly to meet a branch 19 of an exhaust pipe 20 passing through the steam generator. The exhaust gases discharged from the cylinder will pass through 60 the exhaust pipe 20 in the steam generator. The exhaust pipe being submerged in water, its heat will be absorbed by the water to change it to steam. To obtain a greater heating surface for the transfer of heat, I 65 preferably connect transverse water tubes 21 diametrically across the branches 19 and exhaust pipe 20. The exhaust pipe passes out of the steam generator and may be connected with the muffler in the usual manner. 70 The steam generator has slits 22 which communicate with water jacket 4 so that the water heated around the cylinder will pass into the generator to be changed to steam. The steam formed in the steam space 75 23 of the steam generator passes out through a steam pipe 24 and its escape is controlled by a throttle valve 25 which may be manipulated from a distance by extension rods 26. The steam pipe is connected with a conduit 80 27 in the cylinder block which communicates with ports 28 leading into the combustion chambers of the cylinders. A steam valve 29 closes each port 28 and controls the passage of the steam into the cylinders. 85

The steam valve may be of any suitable design preferably of the same type as the intake and exhaust valves 10 and 12 except that two valve heads are provided for each valve to counter-balance the pressure of the steam 90 tending to force the valve open. This valve consists of a main head 29 resting on a seat 30 and a secondary valve head 31 resting on a seat 32. The main valve 29 closes port 28 and controls the admission of steam into the 95 cylinders. The secondary valve 31 seals the port against leakage of steam along a stem 33 which depends from the valve heads through a stuffing box 34 to the outside of the cylinder block. When steam valve 29 is 100 closed, the downward pressure of the steam on the secondary valve head 31 will balance 105

the upward pressure on the main valve head 29 and thus prevent it from being raised from its seat. Each steam valve is held in closed position by a spring 35 having its upper end bearing against a packing nut 36 of stuffing box 34 and its lower end bearing in a retainer cup 37 secured to the lower end of the stem by a pin 38 passing through the stem. The valve is opened by a plunger 39 which, during the operation of the engine, is raised at the proper time by a cam 40 on the cam shaft to admit steam into the cylinder.

Steam generator 23 is preferably made in two sections, a section 41 which carries the exhaust pipe 20 and a section 42 which forms the steam space of the generator. Water may be fed to the steam generator through an inlet pipe 43 connected to the section 41.

The operation of the engine is as follows: 20. The firing order of the cylinders is 1, 3, 4, 2 and the cams on the cam shaft open and close the valves at the proper time to accord with this firing order. Assuming that cylinder No. 1 at the left hand end of Figure 3 has fired, the steam valve will then open immediately after firing to admit steam in the cylinder, the steam being under greater pressure than the pressure of the ignited gases in the cylinder. The period of admission of steam may be varied. Efficient results may be obtained from an admission period of about 20° of the turning movement of the crank. After the lapse of this period the steam valve closes and the power stroke of the piston in cylinder No. 1, under the pressure of the ignited gases and the steam, continues to the end, at which time the exhaust valve is opened by its cam. The time at which the exhaust valve opens may also be varied to meet the requirements of the various designs of engines. Upon opening of the exhaust valve, the gases and steam are forced out of the cylinder by the upward or exhaust stroke of the piston. As the gases and steam are exhausted from the cylinder, they pass through the exhaust port 11, branch 19 and exhaust pipe 20. The heat produced by the combustion of the gases is absorbed by the water surrounding the cylinder, the water above the combustion chamber and the water around the exhaust conduits. After the gases and steam have been exhausted from the cylinder, the exhaust valve is closed and the intake valve is opened by its cam. The piston then moves downward on its suction stroke and draws fresh fuel gases into the cylinder through the intake port 9 and the intake valve 10, after which the intake valve closes and the piston compresses the gases on its upward stroke. When the piston has reached its uppermost position again, the gases are ignited by a spark plug in the usual manner, after which steam is again admitted and the cycle of operation of the piston is repeated. A similar action of the steam and

fuel gases takes place in the other cylinders of the engine and the heat produced by the combustion of the gases is absorbed by the water surrounding the cylinders, the branches 19 and exhaust pipe 20. The commingling of steam and ignited fuel gases has the effect of tending to prevent a carbon deposit in the cylinders. The cylinders are thus kept practically free of carbon deposit and the trouble resulting from carbon-choked cylinders is avoided.

The simultaneous functions of the various cylinders and their sequence are diagrammatically shown in Figure 7. It will be noted at the left hand end of this view that while the piston in cylinder 1 is working or producing "Power" under the pressure of steam and gases, the piston in cylinder 2 is exhausting the gases; in cylinder 3 it is compressing the gases and in cylinder 4 it is on the suction stroke and is drawing in a charge of fresh fuel gases. The simultaneous functions in the four cylinders are "Power" in cylinder No. 1, "Exhaust" in cylinder No. 2, "Compression" in cylinder No. 3, and "Intake" in cylinder No. 4. During the exhaust stroke in cylinder No. 1, the functions in the other cylinders may be readily ascertained from Figure 7 and likewise during the intake and compression strokes. If the length of Figure 7 is graduated with 360 graduations, this being equivalent to 1 revolution or 360°, the exact time at which the different functions begin, may be readily ascertained.

It will be seen that the engine just described will utilize the waste heat of the exhaust gases and conduction for generating steam, and that by causing the steam to work on the same piston as the fuel gases, the tendency is to prevent formation of a carbon deposit and a simple and compact engine is produced.

While I have described my invention as taking a particular form, it will be understood that the various parts may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. In an internal combustion engine provided with cylinders, intake and exhaust gas controlling valves and a cam shaft for actuating the valves; a steam generator mounted on the cylinders and having its bottom wall forming the upper wall of the combustion chambers of the cylinders; steam controlling valves communicating with the generator and the cylinders and operatively connected with the cam shaft for admitting steam into

the cylinders, and a conduit connected with the exhaust gas controlling valve and passing through the steam generator.

2. In an internal combustion engine provided with cylinders, water jackets around the cylinders, intake and exhaust gas controlling valves and a cam shaft for actuating the valves; a steam generator mounted on the cylinders and having its bottom wall forming the upper wall of the combustion chambers of the cylinders and its interior communicating with the water jackets; steam controlling valves communicating with the generator and the cylinders and operatively connected with the cam shaft for admitting steam into the cylinders, and a conduit connected with the exhaust gas controlling valve and passing through the steam generator.

20 3. In an internal combustion engine provided with cylinders, intake and exhaust gas controlling valves and a cam shaft for actuating the valves; a steam generator mounted on the cylinders; steam controlling valves communicating with the generator and the cylinders and operatively connected with the cam shaft for admitting steam into the cylinders; a conduit connected with the exhaust gas controlling valve and passing through the steam generator, and a series of transverse water tubes connected diametrically across the conduit.

25 4. In an internal combustion engine provided with cylinders, intake and exhaust gas controlling valves and a cam shaft for actuating the valves; a steam generator mounted

on the cylinders; steam conduits communicating with the generator and the cylinder; a main valve in a wall of each conduit for controlling the passage of steam into the cylinders; a slidable stem depending from the valve and passing transversely through the conduit; a secondary valve fixed with the stem for sealing the conduit around the stem; resilient means for keeping the valves in closed position, and means operatively connecting the stem with the cam shaft for opening the valves.

5. In an internal combustion engine having combustion chambers, gas controlling valves communicating therewith, a cam shaft for actuating the valves and a steam generator mounted on the combustion chambers; means for supplying steam to each combustion chamber including a conduit communicating with the generator and having a port communicating with the combustion chamber; a valve stem, adapted to be reciprocated by the cam shaft, extending through the conduit; a valve on the stem for closing the port; a spring encircling the valve stem for keeping the valve in closed position; and a balancing head carried by the valve stem and disposed in the wall of the conduit opposite the port, whereby the pressure exerted by the steam on the head will counterbalance the steam pressure on the valve and prevent the steam from forcing said valve open.

In testimony whereof I have signed my name to this specification.

JOHN N. FULLER.
